CIRCUIT INTERRUPTER

Paul J. Glaister, Edgewood, and Herbert L. Rawlins, Wilkinsburg, Pa., assignors to Westinghouse Electric & Manufacturing Company, East Pittsburgh, Pa., a corporation of Pennsylvania.

Application November 3, 1934, Serial No. 751,306

24 Claims. (Cl. 200—150)

Our invention relates to circuit interrupters and particularly to expulsion circuit breakers of the type which utilize an explosive blast of arc extinguishing gas for effecting the extinguishment 5 of the arc which is established incident to the opening of the controlled circuit.

Expulsion circuit interrupters provide the solution to a problem which has, in the past, presented great difficulties to the art, namely, the provision of a reliable yet inexpensive circuit interrupting device of large arc extinguishing capacity. The commercial forms of these devices vary widely, but essentially, each comprises means for defining the walls of a chamber or 15 arc passage, means for establishing an arc therein, and means for producing an explosive blast of arc extinguishing gas through the arc to effect its extinguishment. The simplest means for securing this blast of arc extinguishing gas consists in the provision of a lining for the chamber of a material which is capable of evolving a 20 suitable gas when placed in proximity to an electric arc.

In the operation of these devices, it has been 25 observed that large current magnitude arcs are extinguished much more efficiently and within a much shorter interval of time than low current magnitude arcs. In fact, certain designs of 30 expulsion circuit interrupters while capable of efficiently extinguishing arcs of very large current magnitude are incapable of extinguishing low current magnitude arcs at all.

This apparent phenomenon has been carefully 35 investigated and its cause has been determined. The blast of arc extinguishing gas which is produced during the circuit opening operation is, generally speaking, a function of the current magnitude of the arc. This relationship, however, holds true only when the arc is so confined 40 by the walls of the arc extinguishing chamber that intimate contact between the arc of the gas evolving lining of that chamber is effected. Thus, when small current magnitude arcs are drawn within arc passages of large cross sectional area, 45 an insufficient volume of gas is evolved to assure their extinguishment.

Knowing the source of the difficulty, it would 50 appear that the whole problem could be solved through the provision of a chamber having a sufficiently small cross sectional area to assure intimate contact between the lining of that 55 chamber and the smallest current magnitude arc which might be drawn therein. Unfortunately, however, the problem is not so simply solved. In order to prevent reasonably high pressures

from being developed within an expulsion device during its operation in interrupting heavy currents, it has been found necessary to provide a chamber which has a cross sectional area not substantially smaller than the cross sectional area of the largest current magnitude arc which may be established therein during the operation of the interrupter.

It is thus necessary to utilize a chamber of substantial size, and as a result efficient operation of 10 the prior art devices at low currents is precluded. To overcome this limitation and to assure efficient operation over a wide range of arc current values, is the principal object of the present invention.

One means for overcoming the difficulty discussed above is to utilize an expulsion type circuit interrupter which is provided with a plunger having a conducting portion for establishing the arc within the arc passage, and an insulating portion which is movable into the passage subsequent to the establishing of the arc therein to restrict its volume and to assure intimate contact between the arc and the gas evolving walls, which define the arc passage. Such a structure 25 is shown in application Serial No. 718,267 of H. L. Rawlins, which was filed on March 30, 1934, and which is assigned to the assignee of the present invention.

In this device, a single means is utilized for 30 moving both the arc drawing and the volume restricting portions of the plunger. A much greater range of satisfactory operation over the earlier devices has thereby been obtained, but even this structure still falls short of accomplishing absolutely reliable operation over as wide a 35 range of current magnitudes as is sometimes desired.

In the preferred embodiment of the present invention a structure resembling the Rawlins device is utilized. The arc drawing means and the volume restricting means comprise, however, separate elements, and they are actuated by separate means. The arc passage utilized in this device has sufficient physical size to accommodate the 45 largest current magnitude arc which might be established therein and each of the arcs incident to the opening of the controlled circuit is established entirely within this passage by the arc drawing means. If the current magnitude of the 50 arc is large, it is quickly extinguished by the large volumes of gas evolved from the lining of the arc passage. If, however, the arc is not quickly extinguished, because of the fact that its current magnitude is low, the volume restricting means 55

is automatically moved into the arc passage, so as to assure intimate contact between the arc stream and the gas evolving lining of the passage. The operation of the volume restricting means 5 is controlled either by a means which is responsive to the volume of gas evolved from the gas evolving lining of the arc passage, or it is controlled by some suitable electro-responsive means or the like. Through this arrangement, efficient 10 operation over a very wide range of current magnitudes is assured, and the prolonged arcing which heretofore accompanied the opening of high voltage circuits carrying low magnitude currents by high capacity expulsion devices is obviated.

Another object of our invention is to provide an improved wide range, expulsion type circuit interrupting device which shall be low in cost, simple to manufacture and maintain, and reliable 20 in operation at all times.

A further object of our invention is to provide an improved expulsion type circuit interrupter which shall utilize a single arc passage and means whereby the volume of that passage may be varied 25 upon the occurrence of predetermined conditions, the volume controlling means being effected by either an electro-responsive, a time-responsive or a pressure responsive means.

These and other objects of our invention will 30 be made more apparent by reference to the following drawings and description of a preferred embodiment thereof. Referring to the drawings:

Figure 1 is a sectional view, partially in elevation, of a single-pole double-break circuit breaker, 35 wherein are embodied the principal elements of our invention;

Fig. 2 is an enlarged sectional view through one of the arc extinguishing structures associated with the circuit breaker shown in Fig. 1;

Fig. 3 is a sectional view taken on the line III—III of Fig. 2;

Fig. 4 is a sectional view taken on the line IV—IV of Fig. 2;

Fig. 5 is an enlarged fragmentary view showing the details of the contact structure utilized in conjunction with the circuit breaker illustrated in the other figures of the drawings;

Fig. 6 is a sectional view corresponding to Fig. 2 of a modified form of our invention;

Fig. 7 is an enlarged sectional view on the line VII—VII of Fig. 6;

Fig. 8 is a fragmentary sectional view, similar to Fig. 6, showing the details of a modified form of latch and latch releasing mechanism for use 55 with the arc extinguishing device shown in Figs. 6 and 7; and

Fig. 9 is a fragmentary perspective view showing the armature and latch assemblage utilized in conjunction with the device illustrated in Figs. 60 6 and 7.

The circuit breaker illustrated in Fig. 1 is of the single-pole, double-break type and includes a suitable cylindrical tank 1, which is provided with a cover 3 rigidly affixed thereto by means, such as 65 the stud bolts 5. A pair of insulator bushings 7 extend through the cover 3 into the interior of the tank, and are supported thereon by means of flanges 9 and bolts 11. A plate member 13 of insulating material closes the lower end of the 70 tank 1, and suitable vent openings 14 are provided for venting the entire structure to the atmosphere.

A combined arc extinguishing device and contact structure 15 is supported upon the lower end 75 of each of the control conductors 16 which forms

a part of the bushings 7. These devices are adapted to cooperate with a bridging member 17, having a pair of upstanding contact portions 19, in order to permit the opening or the closing of the electrical circuit through the breaker. The 5 bridging member 17 is actuated by a suitable pull-rod 21 and operating mechanism (not shown). In order that the various structural details of the arc extinguishing and contact structures 15 may be more clearly visible, these 10 devices have not been illustrated in exact proportion, but have been enlarged somewhat from their normal size.

The preferred form of the arc extinguishing and contact structure is shown particularly in 15 Figs. 2, 3, 4, and 5. It includes a cast metallic outer casing 23 which is substantially cylindrical in form, and which is adapted to serve as a support for the remaining portions of the device, and a plurality of plates 25 of insulating material 20 which are assembled, one upon the other, in order to define the walls of an arc passage 27, (excepting a top plate which is provided with a slotted vent opening cut therein). Each of the plates comprises a flat circular member of hard fibre 25 or other insulating material which is formed from an insulating material which is capable of evolving an arc extinguishing gas when placed in proximity to an electric arc. Five circular openings are provided in each of these plates, the 30 outer openings serving to engage insulating studs 29 which are utilized for holding the plates together, and for affixing them to a flange member 31 which is rigidly secured to the lower end of the casing 23. The central openings in each of 35 the plates align to define the arc passage proper 27. These central openings are slightly larger in cross-sectional area than the upstanding contact portions 19 of the bridging member 17 which are adapted to move therethrough during the 40 normal operation of the device. In order to facilitate the entry of these contact portions 19 into the arc passage 27, the lower end of the central opening in the bottom plate 25 is flared.

The upper plate 25 is provided with a cut out 45 portion 33 which serves to form a vent opening for preventing the building up of dangerous high pressures in the arc passage during the circuit interrupting operation. Insulating materials other than hard fibre may be used for forming 50 the plates 25 with success, but we have found that the ability of hard fibre to evolve large quantities of arc extinguishing gas when exposed to an electric arc, while at the same time maintaining its insulating qualities, particularly recommends 55 that material.

The contact structure associated with each of the devices 15, as shown particularly in Figs. 2, 4 and 5, comprises a pair of pivotally supported finger members 35, biased toward each other by 60 suitable springs 37 which engage recesses in the contact members and in the walls of the casing 23. Each of the fingers 35 is provided with a downwardly projecting portion 38 which is adapted to cooperate with the edges of recesses 39 65 formed in the flanged portion of the main casing in order to limit the motion of the fingers toward each other. Suitable flexible shunts 41 connect the fingers with the casing 23, and when the breaker is in the closed circuit position, as is 70 shown in Figs. 4 and 5, each set of opposed fingers 35 engage opposite sides of each of the cooperating upstanding contact portion 19 of the bridging member.

A supporting clamp 43 is cast integral with 75

each of the main casings 23 in order to permit the combined contact structure and arc extinguishing devices 15 to be supported on the lower end of the conductors 16 extending through the insulating bushings 7. The upper end of each of the casings 23 is closed by means of a cap member 45 which is screwed thereon, this cap member being provided with an adjustable, spring biased valve 47 of the ball type for controlling the rate at which air may be drawn into or taken from the upper portion of the chamber 49 within the casing 23. The interior portion of the cap member 45 comprises a tubular member 51, the outer edges 53 of which are threaded for engaging a spring 55 which is positioned within the casing, and the interior of which is machined so as to define a cylindrical chamber 57.

The means for decreasing the volume of the arc passage during the operation of the circuit interrupting device comprises a rod member 59 of an insulating material such as hard fibre which liberates gas when exposed to an electric arc and has a guide member 61 affixed thereto at its upper end. This guide member is adapted to move freely in the large passageway or chamber 49 within the main casing 23, and has a portion 63 which is adapted to cooperate with the cylindrical chamber 57 formed in the cap member in order to give a dashpot action during its operation. The spring 55 engages the upper surface of the guide member 61 and serves to bias the insulating member 59 in the direction of the arc passage.

In the several figures of the drawing the various structural features of the circuit interrupter are shown in the closed circuit position. Upon the occurrence of an overload or other condition, which is capable of causing the circuit breaker actuating means to move the bridging member 17 toward the open circuit position, the upstanding contact portion 19, which engages each of the two pairs of cooperating contact fingers 35, is moved toward the open circuit position, and when those portions disengage the cooperating fingers, an arc is established within each of the arc passages 27. The insulating rod 59, which comprises the volume restricting means for each of the devices, does not move downwardly into the adjacent arc passage 27 immediately following the movement of the upstanding contact portion normally abutting thereagainst, because of the restraining action of the dashpot formed by the cooperating piston and cylinder portions 63 and 57.

If the overload producing the operation of the breaker is one of large current magnitude, the arc which is established in each of the arc passages is of large cross-sectional area and thereby causes the evolution of a large amount of arc extinguishing gas from the gas evolving lining of each of the two passages. This gas creates a pressure which is transmitted to the lower surface of the guide member 61 for the volume restricting means, and if the magnitude of the arc is sufficiently large that the volume restricting means is not necessary to effect its extinction, the movement of that means into the arc passage is entirely prevented, the spring 55 being properly calibrated with respect to the other dimensions of the device.

If, however, the arc which is established within each of the arc passages is of low current magnitude, a comparatively small amount of gas would be evolved, and the pressure resulting from this will be incapable of effecting any substantial

retarding of the normal downward movement of the volume decreasing means, and as soon as the dashpot action has persisted for a predetermined time, depending upon the setting of the spring valve 47, that means will be free to move into the associated arc passage under the influence of its biasing spring. The immediate result of this movement is to decrease the dimensions of the arc passage very materially and to assure an intimate contact between the arc and the gas 10 evolving lining of the arc passage. As a result, an adequate volume of arc extinguishing gas is made available for effecting the extinguishment of each of the two arcs within a short period of time. 15

The amount of time delay introduced into the operation of the volume decreasing means by the dashpot means is variable over a comparatively wide range, but is usually adjusted so as to introduce a delay of perhaps 3 to 10 cycles in the operation of that means. Since large current arcs are usually extinguished within not more than two or three alternations, this assures that the operation of the device will be reasonably uniform as to arcing time, and will be equally 25 efficient upon either high or low currents.

The provision of the vent in the upper plate 25 immediately adjacent the point at which the arc is initially established aids in preventing the rapid development of undesirable high pressures 30 within the arc extinguishing device during its operation, and, in addition, it causes the outwardly flowing arc extinguishing gas to flow through the arc passage substantially longitudinally, thus effecting an extremely turbulent intermixing of the arc with the arc extinguishing gas, and as is well known in the art, thereby aiding the process of arc extinction. 35

If desired, the dimensions of the guide portion 61 of the volume restricting means may be made 40 sufficiently large to prevent any piston action between that member and the casing 23. This arrangement has a tendency to speed up the operation of the breaker somewhat, but either arrangement is quite satisfactory. 45

The modified form of our invention illustrated in Figs. 6 through 9 operates in essentially the same manner as the previously described structure. Each of the combined arc extinguishing and contact structures 115 comprise a cylindrical 50 metallic casing 123 which is closed at its upper end by a suitable cap member 145 and is provided with a flanged member 131 for supporting the associated arc extinguishing device. The dimensions of this flanged portion 131 are the same 55 as those of the similar member 31 in the previously described embodiment, and a plate type arc extinguishing structure of exactly the same form is preferably utilized therein. Likewise, the contact structure is essentially the same and 60 comprises a pair of pivoted fingers 135 biased toward each other by suitable springs 137.

The arrangement of the volume decreasing means is, however, somewhat different. The volume decreasing member 159 which enters the arc passage 27 is a cylindrical rod of insulating material, such as hard fibre, which is supported upon a metallic guide rod 175 to which is affixed a latch engaging member 177 intermediate its ends and a piston member 161 at its upper end. 70 The piston member 161 is adapted to engage the walls of the upper portion of the main casing 123 and is biased downwardly in the direction of the associated arc passage 27 by means of a suitable spring 155, one end of which engages 75

the cap portion 145. The volume decreasing means is prevented from moving under the biasing action of this spring by an electro-responsive trip unit 179, which includes a pivoted latch member 181.

The various portions of the electro-responsive trip unit 179, which constitute the control means for the volume decreasing means, are disposed within a metallic outer casing 183, which is bolted to the main casing 123 of a contact structure and arc extinguishing device. The latch 181, mentioned above, is pivotally supported at the inner end of this casing 183 and is released by movement of an armature 185, shown particularly in Fig. 9. A compression spring 187 biases this armature toward the latched position and it is moved to the unlatched position by the attraction of a coil 189 which is energized by suitable relay means only during the occurrence of moderate overloads. By this means the biasing spring 187 is effective to hold the device in the latched position except when the magnitude of the current flowing in the controlled circuit lies within a predetermined range, which range is determined by the operational characteristics of the device.

The operation of the preferred form of our invention is essentially the same as that described above. Upon the occurrence of an abnormal condition capable of effecting an operation of the main breaker mechanism, the bridging means 17 automatically moves downwardly, taking with it the upstanding contact portions 19. An arc is thus immediately established between the contact fingers 135 and the upper end of each of these contact portions, which arc is progressively lengthened within each of the arc passages 27 as the opening operation progresses. If the current magnitude of these arcs is sufficiently large, the relay means for effecting the energization of the holding coil 189 for each of the latches 181 does not operate, and as a result the two latches remain in the latched position, thereby preventing any movement of the volume decreasing means during the operation of the breaker. The range of currents during which the coils 189 are energized to effect the release of the latches 181 is carefully calibrated in order that the volume decreasing means shall be restricted from movement only when the current magnitude of the overload is sufficiently large to assure rapid extinction of each of the arcs drawn within the arc passages 27.

As a further means for preventing the operation of the device from taking place at a too rapid rate, the piston portion 161 of the volume decreasing means fits tightly against the adjacent walls of the main casing. The pressure of the gas which is evolved within the arc passage during the operation of the device is thus transmitted directly to the volume decreasing means, and that means is prevented from moving when the large current magnitude arcs have been established therein, even if the latch means should become inoperative.

In certain applications, it is desirable that the volume decreasing means shall not move into the arc passages until a predetermined time interval has elapsed subsequent to the establishing of an arc within those passages. In the latched type of device just described, this may be conveniently accomplished through the provision of a dashpot piston 191 and a cylinder 193, as is shown in Fig. 8. With this arrangement, the downward movement of the member 159, which decreases

the volume of the arc passages 27, is positively prevented from taking place until a certain definite interval of time has elapsed subsequent to the establishing of an arc within each of those passages.

The volume reducing members 59 and 159 are preferably formed of hard fibre or similar material. By doing this the maximum possible amount of arc extinguishing gas is made available during each circuit opening operation, and the maximum possible efficiency of the device is attained. Refractory insulating material may likewise be used, however, with reasonable success, but regardless of what material is used there should be some clearance between the volume reducing means and the walls of the arc passage when that means moves therein. Through the provision of clearance it is possible for the arc extinguishing gas to flow freely through the arc stream, and snuffing of the arc, with the undesirable resultant voltage transients, is prevented.

From the foregoing, it will be seen that we have disclosed the details of an improved form of expulsion circuit interrupting device which is capable of satisfactory operation over a very wide range of current magnitudes. Our improved breaker includes means for defining the walls of an arc passage of a fixed volume and a separate means for decreasing the volume of that passage upon the occurrence of certain predetermined conditions, in order to assure intimate contact between the walls of the arc passage and the arc stream itself. Preferably, the arc passage is lined with a gas evolving material in order to assure an adequate volume of arc extinguishing gas during the operation of the device.

In one form of our invention, the volume decreasing means is operable to move into the arc passage only after a predetermined time delay, which depends, in part, upon the amount of arc extinguishing gas which is evolved from the lining of the arc passage, the amount of this gas being one measure of the operational ability of the breaker.

In another modification of our invention, the movement of the volume decreasing means is made responsive to the electrical conditions in the controlled circuit, and in a further modification, it is made responsive to the electrical conditions in that circuit, and at the same time is controlled in its operation by a time delay means.

It will be apparent to those skilled in the art that numerous modifications of our invention may be made without departing from the broad principles which we have disclosed. It is our intention, therefore, that the language of the accompanying claims shall be accorded the broadest reasonable construction, and that our invention shall be limited only by what is expressly stated therein and by the prior art.

We claim the following as our invention:

1. In a circuit interrupter, rigid means for defining the walls of a passage having substantially fixed dimensions, means for establishing an arc within said passage, means, normally disposed without said passage, which is movable into said passage to decrease the volume thereof during the operation of said interrupter, and actuating means for said movable means including means whereby said movable means is moved into said passage only following the establishing of a low current magnitude arc therein.

2. In a circuit interrupter, means defining a

passage having substantially fixed walls, means for establishing an arc within said passage, means movable into said passage to decrease the volume thereof during the operation of said interrupter, and actuating means for said movable means including means operable a predetermined time after arcs of predetermined current magnitudes have been established within said passage to move said movable means therein.

3. In a circuit interrupter, means defining a passage having substantially rigid walls, at least a portion of said passage being lined with a material capable of evolving an arc extinguishing gas when placed in proximity to an electric arc, means for establishing an arc within said passage, means movable into said passage during the operation of said interrupter to decrease the volume of said passage and to effect an intimate engagement between the arc and said gas evolving lining, and actuating means for said movable means including means for causing a predetermined time interval to elapse subsequent to the establishing of said arc before said movable means is moved into said passage.

4. In a circuit interrupter, means defining the walls of an arc passage, means for establishing an arc within said passage, means, normally positioned without said passage, which is movable into said passage to decrease the volume thereof during the operation of said interrupter, actuating means for said movable means, and electro-responsive means for preventing said actuating means from moving said movable means into said arc passage except during the existence of certain predetermined conditions.

5. In a circuit interrupter, means defining the walls of an arc passage, means for establishing an arc within said passage, means, normally positioned without said passage, which is movable into said passage to decrease the volume thereof during the operation of said interrupter, means for biasing said movable means into said passage, and electro-responsive means for preventing said biasing means from moving said movable means into said arc passage except upon the occurrence of predetermined conditions.

6. In a circuit interrupter, means defining the walls of an arc passage, means for establishing an arc within said passage, means movable into said passage to decrease the volume thereof during the operation of said interrupter, actuating means for moving said movable means into said passage, and means including a dashpot for limiting the speed at which said movable means may be moved by said actuating means.

7. In a circuit interrupter, means defining the walls of an arc passage, means for establishing an arc within said passage, means, movable into said passage to decrease the volume thereof during the operation of said interrupter, actuating means for moving said movable means into said passage, and time delay means for preventing said actuating means from moving said movable means into said passage until a predetermined period of time has elapsed following the establishing of an arc therein.

8. In a circuit interrupter, rigid means, at least partially of insulating material, for defining the walls of an arc passage, means for establishing an arc within said passage, a plunger means, which is at least partially of insulating material, and which is adapted to be moved into said arc passage to decrease the volume thereof during the operation of said interrupter, and actuating means for said interrupter including means oper-

able after a predetermined time interval has elapsed following the establishing of an arc within said passage to move said plunger means therein.

9. In a circuit interrupter, means for defining the walls of an arc passage which is lined with insulating material, means for establishing an arc within said passage, a plunger means, which is at least partially of insulating material, and which is adapted to be moved into said arc passage to decrease the volume thereof during the operation of said interrupter, actuating means for moving said plunger means into said passage, and time delay means for preventing said actuating means from moving said plunger means into said passage until a predetermined period of time has elapsed following the establishing of an arc therein.

10. In a circuit interrupter, fixed means, at least partially of insulating material, for defining the walls of an arc passage, means for establishing an arc within said passage, a plunger means, which is at least partially of insulating material, and which is adapted to be moved into said arc passage to decrease the volume thereof during the operation of said interrupter, spring means for biasing said plunger means into said passage and electro-responsive means for preventing said actuating means from moving said movable means into said passage until a predetermined period of time has elapsed following the establishing of an arc therein.

11. In a circuit interrupter, means defining a passage having substantially rigid walls, at least a portion of said passage being lined with a material capable of evolving an arc extinguishing gas when placed in proximity to an electric arc, means for establishing an arc within said passage, means, normally disposed without said passage, which is movable into said passage during the operation of said interrupter to decrease the volume of said passage and to effect an intimate engagement between the arc and said gas evolving lining, actuating means for said interrupter including means for moving said movable means, and electro-responsive means for preventing said movable means from being moved into said passage except during the existence of certain predetermined conditions.

12. In a circuit interrupter, means defining a passage having substantially fixed walls, at least a portion of said passage being lined with a material capable of evolving an arc extinguishing gas when placed in proximity to an electric arc, means for establishing an arc within said passage, means, normally disposed without said passage, which is movable into said passage during the operation of said interrupter to decrease the volume thereof and thereby effect an intimate engagement between the arc and said gas evolving lining, means for biasing said movable means into said passage, and electro-responsive means for preventing said biasing means from moving said movable means except upon the occurrence of predetermined conditions.

13. In a circuit interrupter, means defining a passage having substantially fixed walls, at least a portion of said passage being lined with a material capable of evolving an arc extinguishing gas when placed in proximity to an electric arc, means for establishing an arc within said passage, means movable into said passage during the operation of said interrupter to decrease the volume of said passage and to effect an intimate engagement between the arc and said gas evolving

- lining, actuating means for moving said movable means into said passage, and time delay means for preventing said actuating means from moving said movable means into said passage until a predetermined period of time has elapsed following the establishing of an arc therein.
14. In a circuit interrupter, rigid means for defining the walls of an arc passage, means for establishing an arc within said passage, means for producing a pressure within said passage following the establishing of an arc therein, means movable into said passage to decrease the volume thereof during the operation of said interrupter, and means operable a predetermined time subsequent to the establishing of said arc to move said movable means into said passage provided that the pressure existing therein does not exceed a predetermined value.
15. In a circuit interrupter, rigid means for defining the walls of an arc passage, means for establishing an arc within said passage, means for producing a pressure within said passage following the establishing of an arc therein, means movable into said passage to decrease the volume thereof during the operation of said interrupter, means for biasing said movable means into said passage, and means for preventing said biasing means from moving said movable means into said passage except upon the occurrence of predetermined conditions, said motion preventing means including a piston, a guide means for said piston, and means for subjecting said piston to the pressure developed within said passage.
16. In a circuit interrupter, rigid means for defining the walls of an arc passage which is lined with insulating material, means for establishing an arc within said passage, means, at least partially of insulating material, which is normally disposed without said passage and which is movable into said passage to decrease the volume thereof during the operation of said interrupter, means capable of evolving an arc extinguishing gas when placed in proximity to an electric arc disposed so as to contact the arc which is established within said arc passage, the gas which is evolved from said means producing a pressure within said arc passage, and means responsive to the pressure developed within said passage for moving said movable means into said passage.
17. In a circuit interrupter, rigid means for defining the walls of an arc passage which is lined with insulating material, means for establishing an arc within said passage, means, at least partially of insulating material, movable into said passage to decrease the volume thereof during the operation of said interrupter, means capable of evolving an arc extinguishing gas when placed in proximity to an electric arc disposed so as to contact the arc which is established within said arc passage, the gas which is evolved from said means producing a pressure within said arc passage, which is substantially proportional to the current magnitude of the arc which is established within said arc passage, means responsive to the pressure developed within said passage for moving said movable means into said passage, and time delay means for preventing said pressure responsive means from moving said movable means into said passage until a predetermined period of time has elapsed following the establishing of an arc therein.
18. In a circuit interrupter, means defining the walls of an arc passage, means for establishing an arc within said passage, means for producing a pressure within said passage following the establishing of an arc therein, means, normally disposed without said passage, which is movable into said passage to decrease the volume thereof during the operation of said interrupter, operating means actuatable to move said movable means into said passage, and means responsive to the pressure developed within said passage for preventing said means from moving said movable means into said arc passage except when said pressure falls below a predetermined value.
19. In a circuit interrupter, rigid means for defining the walls of an arc passage, means for establishing an arc within said passage, means for producing a pressure within said arc passage following the establishing of an arc therein, said pressure being proportional to the current magnitude of the arc, rigid means of insulating material, normally disposed without said passage, which is movable into said passage to decrease the volume thereof during the operation of said interrupter, means for moving said movable means into said passage and means responsive to the pressure developed within, said passage for controlling the operation of said means for moving said rigid volume restricting means.
20. In a circuit interrupter, rigid means for defining the walls of an arc passage, means for establishing an arc within said passage, means, at least partially of insulating material, which is normally disposed without said passage and which is movable into said passage to decrease the volume thereof during the operation of said interrupter, means capable of evolving an arc extinguishing gas when placed in proximity to an electric arc disposed so as to contact the arc which is established within said arc passage, the gas which is evolved from said means producing a pressure within said arc passage, which is substantially proportional to the current magnitude of the arc which is established within said arc passage, means for biasing said movable means into said arc passage, and means responsive to the pressure developed within said arc passage during the circuit opening operation for preventing said biasing means from moving said movable means except upon the occurrence of predetermined conditions.
21. In a circuit interrupter, rigid means for defining the walls of an arc passage which has a length at least several times its greatest width, means for establishing the arc incident to each opening operation of said interrupter within said passage, means of insulating material which is normally disposed without said passage and which is movable longitudinally into said passage to decrease the volume thereof during the operation of said interrupter, actuating means for said movable means, and means whereby said actuating means is prevented from moving said movable means into said arc passage except when the current magnitude of the arc which is established therein is less than a predetermined value and said arc has existed within said arc passage for a predetermined interval of time subsequent to its establishment therein.
22. In a circuit interrupter, rigid means for defining the walls of an arc passage which has the general form of a prism, the length of said passage being at least several times its greatest cross sectional dimension, a rod member normally disposed without said passage and movable longitudinally into and through said passage to decrease the volume thereof during the operation of said interrupter, said rod member being formed

at least in part of insulating material and having a cross sectional area which is less than the cross-sectional area of said arc passage, actuating means for moving said rod member and means whereby said actuating means is prevented from moving said rod member into said arc passage except when the current magnitude of said arc is less than a predetermined value and said arc has existed within said arc passage for a predetermined interval of time subsequent to its establishment therein.

23. In a circuit interrupter, rigid means for defining the walls of an arc passage which is substantially cylindrical in form, contact means movable through said arc passage to establish the arc incident to each opening operation of said interrupter therewithin, a cylindrical rod member normally disposed without said passage and movable longitudinally into and through said passage to decrease the volume thereof during the operation of said interrupter, said rod member being formed at least in part of insulating material, having a less cross sectional area than said arc passage, and being adapted to be positioned concentric with said arc passage when it is moved into and through that passage, actuating means for said movable rod member, and means whereby said actuating means is prevented from moving said rod member into said arc passage except when the current magnitude of said arc is less than a predetermined value and said arc has existed within said arc passage for a pre-

determined interval of time subsequent to its establishment therein.

24. In a circuit interrupter, rigid means for defining the walls of an arc passage which has the general form of a prism, the length of said passage being at least several times its greatest cross-sectional dimension and at least a portion of said passage being lined with a material capable of evolving an arc extinguishing gas when placed in proximity to an electric arc, means for establishing the arc incident to each opening operation of said interrupter longitudinally within said passage, a rod member formed at least in part of insulating material which is movable longitudinally into and through said passage during the operation of said interrupter to decrease the volume of said passage and to effect an intimate engagement between the arc and said gas evolving lining, said rod member being normally disposed without said arc passage and having a cross-sectional area which is less than the cross-sectional area of said passage, actuating means for moving said movable means, and means whereby said actuating means is prevented from moving said movable means into said arc passage except when the current magnitude of said arc is less than a predetermined value and said arc has existed within said passage for a predetermined interval of time subsequent to its establishment therein.

HERBERT L. RAWLINS.

DISCLAIMER

2,042,335.—*Paul J. Glaister, Edgewood, and Herbert L. Rawlins, Wilkinsburg, Pa.*
CIRCUIT INTERRUPTER. Patent dated May 26, 1936. Disclaimer filed
October 31, 1936, by the assignee, *Westinghouse Electric & Manufacturing
Company*.

Hereby enters this disclaimer to claims 1, 4, 5, 11 and 12 of the specification.
